ILLUMINATED SIGNAL

Lawrence L. Bray, Waukesha, Wis.

Application November 6, 1935, Serial No. 48,594

1 Claim. (Cl. 177—329)

My invention relates to illumination and signaling devices and has among its objects and advantages the provision of an improved accessory for conventional flash-lights.

5 In the accompanying drawing:

Figure 1 is a side elevation of a conventional flash-light showing my invention attached thereto, and

10 Figure 2 is an enlarged sectional view taken along the line 2—2 of Figure 1.

In the embodiment selected to illustrate my invention I make use of a conventional flash-light 10 including the usual threaded head 12 for the reception of the threaded part of the mounting for the converging lens usually associated with flash-lights. This lens is not shown since it forms no part of the present invention.

I provide a tapered member 14 circular in cross-section and provided with a metallic flange 20 about its lower end which flange is riveted to the member at 18. I prefer to make the member 14 of celluloid having a colored area 20 and a clear area 22. The area 20 is red in color. I offset the flange 16 at 24 to provide a threaded flange 26 having threaded relation with the head 12.

25 In Figure 2 the offset 24 presses the flange 28 of the reflector 30 against the end of the head 12. Within the upper end of the member 22 I position a reflector 32 having a cone-shaped part 34 extending the full length of the clear area 22. The other end of the reflector 32 is tapered at 36 to conform to the angularity of the member 14. I provide a metallic cap 38 which extends over 30 the small end of the member 14 and is provided with an opening 40 for the reception of a wood screw 42. This screw is anchored in the wooden

reflector 32 and the head of the screw lies within a depression 44 in the top of the cap 38. The tubular part 32 of the reflector is painted white for the purpose of reflecting light areas in the direction of the clear area.

5 In operation the member 14 may be connected with the flash-light and employed for signaling purposes. When the bulb 46 is illuminated the area 20 provides a red light which may be used for signaling purposes while the clear area 22 10 gives a white light which may be used for general illumination.

My invention provides a convenient signaling device of a portable nature while the clear area 22 provides illumination for identifying objects 15 and for reading purposes. The construction is exceedingly simple, light in weight and may be connected with conventional flash-lights.

Without further elaboration, the foregoing will so fully explain my invention that others may by 20 applying current knowledge readily adapt the same for use under various conditions of service.

I claim:

A device of the type described comprising a tubular member of transparent material having 25 means for connection with a flashlight, said tubular member having a colored area and a clear area, the clear area being located at the end of the tubular member remote from the flashlight, and a conically shaped reflector positioned inside the tubular member at the end 30 remote from the flashlight with its apex pointing in the direction of the flashlight, said reflector being shaped to reflect light rays in the direction of the clear area.
